UNITED STATES PATENT OFFICE.

ALEXANDER B. CARSTENS, OF MONTEREY, MEXICO, ASSIGNOR TO THE AMERICAN METAL COMPANY, LIMITED, OF NEW YORK, N. Y., A CORPORATION OF NEW YORK.

OPEN-SIDE WATER-JACKET FOR SMELTING-FURNACES.

1,331,803.

Specification of Letters Patent.

Patented Feb. 24, 1920.

Application filed October 1, 1918. Serial No. 256,438.

To all whom it may concern:

Be it known that I, ALEXANDER B. CARSTENS, a citizen of the United States, residing at Monterey, N. L., Mexico, have invented certain new and useful Improvements in Open-Side Water-Jackets for Smelting-Furnaces; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in water jackets for smelting furnaces. This invention has to do with means for cooling the sides of the lower part of the furnace so that it is unnecessary to consider the reactions that take place in the shaft when in operation. It should be stated, however, that cooling must be provided in order to obtain satisfactory results in a furnace of this character.

In smelting furnaces it is desirable to provide water jackets to that part of the furnace where temperatures are high and where unprotected walls would be subjected to the action of the molten metal when the furnace is in operation. The present recognized practice is to build a hollow jacket that usually reaches from the crucible upwardly to the lower part of the brick work of the furnace shaft. The jackets as at present used are hard to clean and this can only be done by closing down temporarily and washing out the jackets. Furthermore, there is no positive means of knowing whether the jacket is full of water or not. The static pressure of the water at the lower end of the jacket is usually much higher than the pressure inside the furnace, so in case the jacket burns through at its lower end on the inside of the furnace the water enters and a violent explosion ensues. This has happened a great many times and these explosions are sometimes attended with loss of life.

The idea of an open side jacket is to provide means for ready cleaning and inspection, but the most important point is that the static head of the water at the lower

end of the jacket amounts to very little and this pressure is not affected by the height of the jacket as in the inclosed type. It is, therefore, possible with my improvement to build a jacket as high as desired without endangering the furnace from high water pressure in the jackets.

Having briefly outlined the invention as well as some of the objects it is desired to accomplish, I will proceed to describe the same in detail reference being made to the accompanying drawing in which is illustrated an embodiment thereof. In this drawing:

Figure 1 is a vertical longitudinal section of a silver lead smelting furnace equipped with my improvement, the furnace being partly broken away for lack of room on the sheet. In this view I have shown what I term the multiple cell jacket.

Fig. 2 is a similar view of the lower part of the furnace but showing a slightly modified type of jacket, being what I term the single cell type.

Fig. 3 is a section taken through one of the jacket members on the line 3-3 Fig. 4, showing the multiple cell type.

Fig. 4 is an exterior or outside elevation of one of the water jacket members of the multiple cell type.

Fig. 5 is a section taken on the line 5-5, Fig. 6 illustrating the single cell type.

Fig. 6 is an exterior elevation of one of the single cell type water jacket members.

Referring first more particularly to Figs. 1, 3 and 4, let the numeral 5 designate the upper part or shaft portion of the furnace in which the material to be smelted is charged. 6 designates the walls of the furnace shaft and 7 designates the open side water jackets which form the wall of the lower portion of the furnace, 8 being the crucible or lower extremity of the furnace from which the molten metal is tapped after there has been a sufficient accumulation thereof. When in operation the cooling water is introduced through a pipe 9 to the uppermost cell as shown, and as soon as the water fills this cell it overflows through the overflow pipe 10 and is carried down to the next cell immediately under the top one, and from here the water cascades down through openings 12 until it reaches the lowest cell

from which the heated water is carried away by an outlet pipe 13.

Referring now more particularly to Figs. 2, 5 and 6, let the numeral 14 designate each of a series of superposed cells of which each member 14 of this type of jacket is composed. These cells are so arranged that they fit closely together and may be cemented or otherwise sealed at the joints to make the jacket perfectly tight. Each cell is open, and therefore, accessible from the outside of the furnace in substantially the same manner as the multiple cell type previously described. In the single cell type, however, if one cell becomes injured, it only need be removed in order to repair the jacket, thus reducing the expense incident to the renewing of a cell to the minimum. Water is introduced through a pipe 15 to the uppermost cell and overflows therefrom through an outlet pipe 16 to the next cell below and so on until the water reaches the lowermost cell from which it is drawn through an outlet pipe 17, each cell between the top and bottom cells having an overflow pipe 16.

As illustrated the complete water jacket surrounding the portion of the furnace below the wall 6 is composed of members of any desired width, one of these members of the multiple cell type being illustrated in Fig. 4, while a member of the single cell type is illustrated in Fig. 6. The vertical abutting edges of these members of each jacket may be joined in any suitable manner in order to form perfectly tight joints. In the single unit members the cells are arranged one above another in such a manner that they nest together, their lower walls being downwardly inclined from the outer ends of the cells, so that they are normally retained in place after they are properly positioned.

Whether the furnace is equipped with the one or the other style or type of open side water jacket, it is supplied with air through a main pipe 18 from which smaller pipes or twyers 19 extend downwardly and enter the lower part of the water jacketed portion of the furnace. When the furnace is being used in the usual way, the fuel and the ore to be treated are charged in at the top as is the regular practice in blast furnaces. My improvement is confined exclusively to the water jacket feature. Hence, in other respects the construction may be of the ordinary or any suitable type.

The burning out of water jackets is a constant source of annoyance and expense and in the present practice or that heretofore in vogue, the whole jacket must be removed as soon as a leak develops. These jackets are very high and unwieldy so that considerable time is lost in changing them. By using an open side water jacket of the

single cell type, as shown in Figs. 2, 5 and 6, the repair of the jacket due to the burning out of a single cell only involves the removal of a small piece of the jacket, thereby saving much time and expense. 70

There are many places where the use of the open side jackets of either the single or multiple cell type would be advantageous, such as the side and end walls of a slag separator as used around lead smelting 75 plants. These jackets may also be advantageously employed in lead refineries for jacketing the side and end walls of the softening and refining furnaces. They may also be used in connection with copper blast 80 furnaces. In fact, they may be used almost in every instance where heretofore it has been the practice to employ the closed jacket.

From the description as heretofore given, 85 it will be understood that the vital feature of the invention consists in the employment of partitions or divisions so arranged as to form cells that are accessible while in use, the said cells being intercommunicating or 90 arranged to overflow successively from top to bottom. This involves the feature of dividing the jacket up into small pockets to obviate water pressures in the jacket that are higher than the pressure in the furnace. 95 The general shape of the jacket may be made to suit the particular furnace to which it is to be applied. This is a matter of manufacture and does not alter the principle of the jacket. 100

Attention is called to the fact that the outlet openings 12 of the cells of the multiple cell type jacket and the outlet pipes 16 of the single cell type, of the adjacent cells are arranged in staggered relation or out of 105 vertical alinement. This is important particularly in the multiple cell type, since if the outlets 12 of adjacent cells were in vertical alinement the overflow from an upper cell would probably drop beyond the cell 110 next below instead of entering it.

Having thus described my invention, what I claim is:

1. The combination with a blast furnace or other similar structure, of a metal water 115 jacket forming the bosh wall of said furnace and consisting of superposed inter-communicating cells.

2. A water jacket for metallurgical furnaces composed of a series of superposed independently removable cells, and forming a 120 wall of said furnace.

3. A water jacket for metallurgical furnaces composed of a series of independently removable cells and forming a wall of said 125 furnace and means for conducting water from the upper portion of any cell to the next cell below, whereby the columns of water in the several cells are non-cumulatively arranged. 130

4. A water jacket for metallurgical furnaces composed of a series of independent cells separably arranged one above the other and forming a wall of said furnace, the wall being inclined for self-sustaining purposes.

5. A water jacket for metallurgical furnaces composed of a series of superposed

separable cells forming a wall of the furnace and arranged to overflow successively from one to the other and from the top to the bottom of the jacket.

In testimony whereof I affix my signature.

ALEXANDER B. CARSTENS.
